CLAIM

I claim the ornamental design for medical port disc, as shown and described.

DESCRIPTION

FIG. 1 illustrates a top forward perspective view of the present invention.

FIG. 2 illustrates a bottom rear perspective view of the present invention.

FIG. 3 illustrates a rear view of the present invention.

FIG. 4 illustrates a frontal view of the present invention.

FIG. 5 illustrates a side view of the present invention.

FIG. 6 illustrates a top view of the present invention; and, FIG. 7 illustrates a bottom view of the present invention.

The drawings set forth a unique design for a medical port disc.

The broken lines shown in the drawings represent portions of the medical port disc and attachments that form no part of the claimed design.
